Hylls.*

UNITED STATES PATENT OFFICE.

FREDERICK S. ANABLE, OF BROOKLINE, MASSACHUSETTS, ASSIGNOR TO NATIONAL BINDING MACHINE COMPANY, OF BOSTON, MASSACHUSETTS, A CORPORATION OF MAINE.

STRIP-SERVING DEVICE.

1,393,002.

Specification of Letters Patent.

Patented Oct. 11, 1921.

Original application filed January 6, 1916, Serial No. 70,554. Divided and this application filed August 23, 1918, Serial No. 251,066. Renewed March 2, 1921. Serial No. 449,238.

To all whom it may concern:

Be it known that I, FREDERICK S. ANABLE, a citizen of the United States, and a resident of Brookline, in the county of Norfolk and State of Massachusetts, have invented an Improvement in Strip-Serving Devices, (Case D,) of which the following description, in connection with the accompanying drawings, is a specification, like characters on the drawings representing like parts.

10 This invention is a division of my co-pending application Serial No. 70,554, filed January 6, 1916, which itself is a division of my application Serial No. 413,798, filed February 1, 1908, now Patent No. 1,168,777.

15 This invention relates to devices or apparatus for supplying strips of paper or other suitable material of any desired length to be applied to packages, bottles, 20 bundles or the like as a wrapping means or as a label or for any other desired purpose, the illustrated embodiment of the invention showing an apparatus provided with means for holding a strip supply previously 25 gummed on one side, such strip being adapted to be withdrawn in selected lengths and further provided with means for moistening the gummed side of the strip as the latter is withdrawn. It is apparent that an 30 ungummed strip of paper or the like might be employed, and the moistening device be utilized for applying adhesive to the side of the withdrawn strip.

35 My invention will be best understood by reference to the following description when taken in connection with the accompanying illustration of one specific embodiment thereof, the scope of the invention being more particularly pointed out in the appended claims.

40 Referring to the drawing,—

Figure 1 is a side elevation of a strip serving apparatus embodying my invention;

45 Fig. 2 is a plan view of a portion of the apparatus shown in Fig. 1;

Fig. 3 is a side elevation, partially in vertical section, of a modified form of the apparatus shown in Figs. 1 and 2; and

50 Fig. 4 is a plan view of a portion of the apparatus shown in Fig. 3.

In the form of my invention herein dis-

closed, means are provided to prevent contact of the free end of the strip with the moistener when the apparatus is not in use. 55

The strip support indicated at 1 may be of any suitable character. Preferably the strip is supported in the form of a roll in a suitable casing upon a base 2, there being suitable tensioning means for the roll, 60 as, for example, a thumb nut 3. Preferably mounted upon the base 2 is a tank or reservoir 4 having operatively connected thereto any suitable moistening device herein represented as a wick 5 arranged in inverted U shape with the ends thereof depending into the tank, the intermediate portion being suitably disposed to maintain the strip as the latter is drawn across the same. Any suitable strip severing means 70 may be provided, as, for example, the blade 6, herein represented as in advance of the moistener.

In the figures of the drawing, I have represented means mounted directly upon the 75 moistener to elevate the strip therefrom when the strip is not drawn upon for use. In Figs. 1 and 2, I have represented the moistener 5 as provided with preferably light and readily yielding spring members 80 7 which, when the strip is not drawn upon, elevate the latter as represented in Fig. 1, but which when the strip is drawn upon readily yields to permit contact of the strip and moistener. If desired, the spring members 85 7 may be arranged in several rows or series and in alternation, so that all portions of the strip may be moistened. The spring members 7 may be mounted in any suitable manner, as in the backing or foundation of the moistener, as indicated at 8 in Fig. 1. The moistener 5 is represented as provided with cut out portions 9 to receive the said spring members when depressed. 90

In Figs. 3 and 4, I have represented pins 95 10 normally elevated as by coil springs 11, thereby to separate the strip from the moistener, the springs 11 being of suitable strength to permit the ready depression of the pins 10 when the strip is drawn upon, 100 thereby to permit contact of the strip with the moistener.

The pins 10 and the springs 11 may be mounted in suitable sockets formed in the

moistener or its support. Any suitable number of such pins may be provided. Herein a transverse row thereof is represented.

When it is desired to utilize the strip, 5 the free end thereof is grasped by the operator and is drawn into contact with the moistener, the springs 7 or 11 yielding to permit such contact of the strip with the moistener. The strip is then drawn across 10 the moistener until the desired length is drawn from the support 1. After severance of the strip, the springs 7 or 11 become at once effective to separate the strip from the moistener.

Having thus described one illustrative embodiment of my invention, I desire it to be understood that although specific terms are employed, they are used in a generic and descriptive sense and not for purposes of limitation, the scope of the invention being set forth in the following claims.

Claims.

1. A strip serving device comprising a strip support, and a moistener in operative 25 relation thereto, said moistener having spring means to effect separation of the strip and the moistener.

2. A strip serving device comprising a strip support, a moistener in operative relation thereto, and strip severing means in advance of the moistener, said moistener having spring means adapted to yield when the strip is drawn across the moistener, but adapted to separate the strip from the 35 moistener after strip severance.

3. A strip serving device comprising a strip support, a moistener in operative relation thereto, and spring means extending through the moistener to and above the 40 upper surface thereof and adapted to sus-

tain the free end of the strip out of contact with the moistener, but adapted to yield when the strip is drawn across the moistener.

4. A strip serving device comprising a strip support, a moistener in operative relation thereto, spring means extending through the moistener to and above the upper surface thereof and adapted to sustain the free end of the strip out of contact with the moistener, but adapted to yield when 50 the strip is drawn across the moistener, and a severing blade 6 in advance of the moistener.

5. A strip serving device comprising a strip support, a moistener and spring means located at the point of strip moistening to 55 effect separation of the strip and the moistener.

6. A strip serving device comprising a strip support, a moistener in operative relation thereto and a severing device in operative relation to the moistener, said moistener having spring means to effect separation of the strip and moistener upon strip severance by said severing device.

7. A strip serving device comprising a strip support, a moistener, a severing device in operative relation to the moistener, and spring means located at the point of strip moistening to effect separation of the strip and moistener upon strip severance. 70

8. A strip serving device comprising a strip support, a moistener, a severing device in advance of but operatively related to the moistener, and spring means located at the point of strip moistening to effect separation of the strip and moistener upon strip severance. 75

In testimony whereof, I have signed my name to this specification.

FREDERICK S. ANABLE.
